COOLER CHEST

Morris N. Wiant, Regis D. Schulte, Benjamin C. Baugh,
Robert R. Deines, and James R. Feimster, Wichita,
Kans., assignors to The Coleman Company, Inc.,
Wichita, Kans.

Filed June 1, 1973, Ser. No. 366,154

Term of patent 14 years

Int. Cl. D7—07

U.S. Cl. D7—77

FIG. 1

FIG. 2

FIG. 3

FIG. 4

FIG. 1 is a front perspective view of a cooler chest showing our new design;

FIG. 2 is a rear perspective view of the cooler chest of FIG. 1;

FIG. 3 is a front perspective view of a second embodiment of our design for a cooler chest, all components other than the top surface of the lid being identical to the embodiment of FIGS. 1 and 2; and

FIG. 4 is an end elevational view of both embodiments, the end views being identical.

The bottom of the cooler chest is substantially plain and unornamented.

We claim:

The ornamental design for a cooler chest, as shown and described.
